ABRAHAM E. CHERNACK, OF PROVIDENCE, RHODE ISLAND, ASSIGNOR TO CHERNACK MANUFACTURING COMPANY, OF PAWTUCKET, RHODE ISLAND, A CORPORATION OF RHODE ISLAND.

LOOM FOR WEAVING TUBULAR FABRIC.

1,088,061.

Specification of Letters Patent.

Patented Feb. 24, 1914.

Application filed March 8, 1912. Serial No. 682,439.

To all whom it may concern:

Be it known that I, ABRAHAM E. CHERNACK, a subject of the Czar of Russia, and resident of Providence, in the county of Providence and State of Rhode Island, have invented certain new and useful Improvements in Looms for Weaving Tubular Fabric, of which the following is a specification.

This invention relates to looms of the circular type, especially for the purpose of weaving tubular fabrics such as hose and for covering cores of metal or other material with woven sheaths, whether the strands employed for the purpose are of fibrous material or a combination of fibrous strands with strands of other material such as metal or paper.

The invention has general reference to the type of loom illustrated and claimed in U. S. Letters Patent No. 920,728, granted to me May 4, 1909. In said patent all of the warp threads are led through guide eyes which extend inwardly toward the center of the machine, and above the shuttles.

An especial object of the present invention is to provide a structure of loom of the type referred to in which the means for taking up the slack thread of the warp is located outside of the plane of the path of the shuttles instead of inside, whereby the changing of bobbins in the shuttle is facilitated, and the warp threads pass more directly from the supply to the weaving point.

Other objects of the present invention are to provide improved automatic stop motions brought into action by the breaking of either a shuttle thread or a warp thread; an improved structure or support for the cam rings to provide a bearing therefor which will be located in the horizontal plane of the point where the cams operate; also to provide an improved structure which will enable a cable or core to be covered by the weaving operation to pass upwardly through the center, or to support a mandrel or holder on which hollow tubing is woven.

Other objects of the invention are to provide improvements in various details of the loom, as will be explained more fully hereinafter.

To these ends the invention consists in the construction and combination of parts

substantially as hereinafter described and claimed.

Of the accompanying drawings, Figure 1 is a vertical section through a loom constructed according to my present invention, parts of the shuttles, and duplications of guides, being omitted to avoid confusion; Fig. 2 is a fragmentary plan view, omitting the guide-wires and their top ring, on a larger scale than Fig. 1; Fig. 3 represents a partial elevation and part section on line 3—3 of Fig. 2; Fig. 4 is a detail plan view of portions of the step motion rings which would occupy a position substantially diametrically opposite the portion of the machine which appears in Fig. 2; Fig. 5 represents a section on line 5—5 of Fig. 4; Fig. 6 is a detail longitudinal sectional view of the stop pin and its tubular support; Fig. 7 is a horizontal sectional view of the shuttle tension device; Fig. 8 represents a section on line 8—8 of Fig. 3; Fig. 9 represents a section on line 9—9 of Fig. 2; Fig. 10 is a detail perspective view to illustrate the structure of the guides in the cylinder; Fig. 11 is a diagram, in substantially the vertical plane of line 11—11 in Fig. 1, to show the development of the cams for actuating the warp thread guides and the relation of the latter to the shuttles.

Similar reference characters indicate the same or similar parts in all the views.

The machine illustrated is intended for a bench machine, and the frame 15 is illustrated as having short legs 16. Of course the machine can be made to stand at any height that may be desired. The bottom 17 of the frame is provided with a central boss 18 in which is tightly fitted, as by being driven in, a hollow spindle 19, which spindle possesses a double function presently described. Removably fitted to the upper end of the spindle 19 is a mandrel 20. Mounted on the hollow spindle 19 is the sleeve portion 21 of the cam carrier or casing, the bottom 22 of said carrier or casing having a rotative bearing upon the bottom 17 of the frame, and having the cylindrical or peripheral casing portion 23. Secured to this cam carrier or casing are an outer cam ring 24 and an inner cam ring 25, the vertical height of these two rings and the outer shell

23 being substantially the same as the sleeve portion 21 on the spindle 19. This structure provides for a center of support at the center of maximum strain; that is, the bearing 5 for the cam casing is located in the horizontal plane of operations of the cams, instead of in a lower plane as in the patent above referred to. This provides for greater stability and less wear of the matter. 10 chine.

The other function of the hollow spindle 19 is to enable it to be employed as a stationary guide through which a cable or other core to have a woven covering applied thereto can be fed upwardly. In other words, the hollow spindle 19 serves as a non-rotary guide for such core or cable and therefore produces no tendency, during the operation of the loom, to rotate such core 15 or cable. When it is desired to weave a tubular fabric having no core, the upper end of the hollow spindle 19 is employed to receive the plug of a mandrel 20, about the upper end of which the weaving then takes 20 place.

Secured to the bottom 22 of the cam support, is a spur gear 26 with which meshes an idle intermediate pinion 27 mounted upon a stud 28 that is supported by the bottom 30. Meshing with the pinion 27 is a pinion 29 which is secured upon a vertical shaft 30 mounted in suitable bearings provided by the frame of the loom, said shaft 30 having also a bevel pinion 31 meshing 35 with a similar pinion 32 secured to a driving shaft 33. A friction clutch driven device of a well known form is employed for the shaft 33, and is sufficiently illustrated in Fig. 3, in which 34 indicates the cone member which is secured to the outer end of shaft 33, a driven belt pulley 35 having an inner surface to cooperate with the cone 34 when the pulley 35 is shifted laterally relatively to the cone 34. The grooved hub 36 40 of the pulley 35 is engaged by an elbow lever 37 pivoted at 38 to a bracket 39 of the bearing in which shaft 33 is mounted. The mechanism for actuating the lever 37 and so starting or stepping the machine will be 45 described hereinafter.

Supported upon and secured to the upper edge of the cylindrical portion of the frame 15 is the guide cylinder 40. This cylinder, instead of being formed with planed vertical grooves for the guides hereinafter described, has secured to its inner wall a circular series of guides 41 (see Fig. 10 in connection with Figs. 1, 2 and 3). These guides are secured to the inner wall of the cylinder 40 by screws 42, their lower ends being held so that the sides of the guides will always be parallel, by a bottom ring 43 which may be secured to the lower ends of the guides by any suitable means. This ring, in connection with the screws 42, keeps the guides in

fixed relative positions so that there can be no binding of the slides which reciprocate vertically in the ways 44 formed in the sides of said guides.

Each of the guides 41 is provided with 76 a pair of oppositely inclined wings 45 which, when the entire series of guides 41 are in assembled positions, form a horizontal circular track or way for the shuttle carriers, such track or way being of course interrupted or cut by the spaces between the guides 41, but not in any such manner as to interfere with the travel of the shuttles. 75

The base plates 46 of the shuttles are tapered at each end as indicated at Fig. 11, 80 so that they may be driven as hereinafter described, and in the same manner as described and claimed in the patent above mentioned. To the back of each plate 46 is secured a lower fixed gib 47 and an upper 85 adjustable gib 48, these two gibs engaging the wings 45 which constitute the shuttle track. The gib 48 is adjusted by means of cone tipped screws 49.

Each plate 46 has secured thereto a bobbin frame 50 provided with bearings 51 for the spindles of the usual paper tubing which supports the ordinary universal wound bobbin. 90

To keep the bobbin thread in close contact with the friction drum or shell 61 hereinafter described, I provide a tension consisting of a presser 52 which is a U-shaped frame pivoted at 53 to the plate 46, one or more springs 54 (see Fig. 3) being employed 95 to hold the horizontal portion of the presser frame in contact with the surface of the bobbin. This presser prevents the bobbin from revolving too freely and consequently disturbing the close contact between the 100 thread and the drum or shell 61 mentioned. Said presser acts, of course, on a bobbin which varies in diameter as the thread is drawn off, but since the spring 54 shortens as the presser moves downwardly, the friction created by the presser becomes gradually less. 105

Referring especially to Figs. 2, 3 and 7, it will be seen that an arm 55 projects from the plate 46. In said arm is rigidly mounted 115 a pin or spindle 56 having a cone base 57 and also having an opposing cone-bushing 58 which is slidably mounted on the spindle but secured so as not to rotate thereon. A spring 59 is coiled about the projecting end 120 of the spindle, and a cap or nut 60 having a cone shaped or tapered outer end engages the threaded end of the spindle and enables the pressure of spring 59 against cone-bushing 58 to be varied. A drum or shell 61 (see 125 Fig. 7) having internal cone-shaped end recesses is mounted on the spindle, said recesses fitting the cones 57, 58. By adjusting the cap 60, the degree of friction which will retard rotation of the drum or shell 61 130

may be varied. I do not limit myself specifically to the cone shape of the friction elements shown, as said elements may possess any suitable form that will enable the necessary friction to be obtained. Also secured to the arm 55 is a bar or plate 62 having a plurality of guides 63 formed therein. Three of said guides are shown as eyes or holes, two of them having openings leading away from the drum 61 and one of them having an opening facing toward said drum. This structure provides a tension for the shuttle thread which provides no direct grip action on the thread and consequently will permit a knot to pass freely. The thread is led from the bobbin through one of the eyes 63 nearest to the arm 55, then around the drum 61 which is preferably roughened, then through the intermediate eye 63, then again around the drum 61, then through the third eye 63, and then through an eye in the outer end of a stop-motion lever 64 which is pivotally connected at 65 to the frame 50, as best shown in Fig. 2.

Owing to the guides 63 being open, and the tapering form given to the end of the nut or cap 60, the thread may be easily passed and located as described. The especial object of the several guides 63 is to hold the several coils spaced and enable the preferably roughened surface of the drum 61 to result in uniform tension, while without such guides the thread wrapped several times about the drum 61 would, owing to its spiral winding, tend to run off at one end of the drum.

The lever 64 is normally held in the position indicated in Fig. 2 by a spring 66, and one arm of said lever is connected by a link 67 with a plunger 68, said plunger extending through the shuttle plate 46 but normally held by the spring 66 with its inner end within the plane of the inner face of the guides 41. As shown in Fig. 3 the plane of the plunger 68 is such that if it were projected beyond the outer face of plate 46, it would pass into the space between the upper and lower wings 45 which form the shuttle track.

As shown by comparing Figs. 2 and 3, a lever 69 is pivotally supported at 70, and has its inner end projecting through a slot (indicated by dotted lines in Fig. 3) formed in one of the guides 41. The extreme inner end of the lever 69 is widened as shown in Fig. 2, and has its under surface beveled to form a cam surface 71. In practice this inner end is beveled in both directions so that the lever 69 would be actuated by the plunger 68 coming in contact with it when traveling in either rotative direction. It will now be understood that if the shuttle thread should break, the spring 66 will at once cause the plunger 68 to be projected toward the right of Figs. 2 and 3 so that its

tip would engage the cam 71 and oscillate the lever 69 on its pivot 70.

Mounted in a tubular bearing 72 projecting substantially radially from the cylinder 40, is a pin or rod 73 having a tapered outer end 74. The inner end of the pin 73 is formed with a socket containing a spring 75 (see Fig. 6) having a tendency to normally project the pin 73. The pin is formed with an annular groove 76 which receives a locking lever 77 (see Figs. 2, 6 and 9) pivotally supported at 78 and pressed inwardly by a spring 79, the tubular bearing 72 being formed or provided with a slot in which the lever 77 rests with its upper edge engaging the annular groove 76. The outer end of the lever 77 projects under the outer end of lever 69 and therefore, whenever the plunger 68, owing to the breakage of a shuttle thread, shifts so that it will, as the shuttle moves along, raise the inner end of lever 69, the outer end of the latter will depress the lever 77 so as to release the pin 73 and permit the spring 75 to project the pin 73 so that its tapered outer end will actuate the same mechanism which is also brought into operation to effect a steppage of the loom if a warp should break as hereinafter described.

The vertical warp thread slides operate substantially the same as described in my patent above referred to, and they in turn drive the shuttles. Said slides are indicated at 80, and they are mounted alternately with the guides 41 so as to reciprocate in the grooves or ways 44 of said guides. Each slide has a pin at its lower end, provided with a roll 81 entering the cam groove or track of one or the other of the rings 24-25. Said pins project alternately in opposite directions so that while the pin of one slide engages the groove of ring 24, the pin of the next slide engages the groove of ring 25, and so on, so that the slides will be alternately actuated in opposite directions in the same manner as described in the said patent. The upper ends of all the slides are provided with tubular pins 82 having rolls 83 on their inner ends. All of said pins project toward the center of the loom, and all of the rolls 83 are in the path of travel of the shuttle plates 46 so that, as the slides are vertically actuated, the rolls will engage the inclined ends of the plates 46 to drive the shuttles in the same manner as in the patent referred to.

The upper edge of the cylinder 40 is thickened and provided with a series of holes 84 (Fig. 2), in which holes are secured the lower ends of inwardly bowed eye-guides 85 (Fig. 3). To steady said guides 85, their upper ends are all connected to a ring 86. Pivotally connected to the upper end of each slide 80 is a wire 87 having a warp thread eye 88 near its upper end and an end portion which is coiled around the curved guide 120

85 so that, as the slides move vertically, the eyes 88 are caused to follow the curves of the guides 85 in order to compensate for the varying distance of the passageway in the 5 tubular pins 82 from the weaving point π . While the function of this portion of the loom is substantially the same as similar devices in the patent referred to, yet this structure involves a very material feature of my 10 present improvement in that the taking up of the slack thread of the warp is caused by mechanism which is located entirely outside of the path of rotation of the shuttle, so as to render the shuttle bobbins more accessible, 15 and providing for a more direct passage of the warp to the weaving point. The warps are indicated by the broken lines α in Fig. 1, and they lead through pins 89 presently described, then through the eyes 88, then 20 through the tubular pins 82 and direct to the weaving point π . It will be seen, that as each tubular pin 82 reaches the horizontal plane of said weaving point and causes a slackening of the warp, the eye 88 which 25 of course moves vertically in unison with the tubular pin 82, is deflected inwardly by its guide 85 so as to take up such slack in the manner described in the patent referred to. But no parts of this mechanism are 30 within the circle of the path of travel of the shuttle and therefore access is readily had to the shuttles at all times. Of course in order to effect this taking up of the slack, the curve of the guides 85 is of a shorter 35 radius than a circle of which the pin 89, or the rib adjacent thereto, would be the center.

I will now proceed to describe how the breakage of a warp would effect the stoppage of the loom:—There are as many pins 40 89 as there are warps, and the eye of each pin, through which eye the warp passes, has an inwardly and upwardly slanting slot, so that said pins practically constitute hooks that will be normally supported by the 45 warps when the latter are taut as indicated by the broken lines in Fig. 1. The pins 89 are mounted in holes in the ring 90 which is supported by the frame of the machine in any suitable manner, said ring being of 50 course stationary. Below the ring 90 is a compound ring 91, 92 supported by suitable lugs 93, the structure being such that the lower member 91 may oscillate upon the lugs 93, while the upper member 92 may oscillate 55 in a groove formed therefor in the member 91. The member 92 has as many holes 94 (see Fig. 4) as the holes in the stationary ring 90, and equally spaced so that any pin 89 may drop into a hole 94 in member 92 60 when the holes are in alinement and such pin has been released by the breakage of its warp. A pin 95 (Figs. 4 and 5) projects downwardly from member 92 through a slot 96 in the member 91, and said pin 95 is 65 connected to a pin 97 projecting downwardly from member 91, by a spring 98, the tension of this spring being to always draw the pin 95 to the end of the slot 96 nearest the pin 97, and consequently normally holding the compound ring so that the two members will 70 move together under normal operating conditions. The oscillation of the compound ring is effected as follows:—A pin 99 (Figs. 2 and 8) projects downwardly from the member 91 and is connected by rod 100 with the strap of an eccentric 101, the latter being mounted to rotate with a gear 102 which, by means of intermediate compound gearing 103, is driven by a pinion 104 on shaft 30. It will therefore be understood that during the 75 operation of the loom, the eccentric will cause constant short oscillations of the compound ring 91, 92. But if a warp breaks and a pin 89 drops into the hole 94 which is being constantly reciprocated underneath it, 80 then such pin serves to lock the member 92 from oscillating, and only the member 91 will oscillate. The ring 90 is provided with upwardly projecting ribs 105, 106 over which the warps α are drawn, and these ribs 85 are of such height, relatively to the length 90 of the pins 89 from their lower ends to the portions which rest upon the warps, that when the loom is running, and running properly, all of the pins 89 are supported 95 so that their lower ends are above the plane of the top of member 92.

Referring especially to Fig. 8, it will be seen that the member 92 has a pin 107 projecting downwardly through a slot 108 in member 91. And a pin or lug 109 carried by member 91 has pivotally connected thereto a lever 110 provided with a cam surface 111. A spring 112 engages a pin 113 projecting from lever 110 and has a normal tendency 105 to hold said lever 110 in the position shown in Fig. 8. So long as the two members 91, 92 are oscillating together, nothing occurs in the mechanism just described. But as soon as member 92 is arrested by a pin 89, 110 its pin 107 of course is also arrested; but since the member 91 continues to oscillate, its lug 109 instantly draws the lever 110 along or toward the left in Fig. 8 so that the cam 111, riding underneath the lower end of 115 pin 107, causes said lever 110 to be depressed. The outer end of the lever 110 is connected by a link 114 to a lever 115 pivoted at 116 and having a catch 117 at its other end. Preferably the connection between the link 114 and lever 110 is a slotted one so that the catch 117 may be raised without material opposition, when the machine 120 is being started as hereinafter described. The cone or tapered end 74 of the pin 73 of 125 the filling stop-motion hereinbefore described, projects to such a position that when the spring 75 projects the pin 73, said tapered end 74 will engage the underside of lever 115 between its pin 114 and the catch 130

end, so as to raise the catch. Consequently it will be understood at this point that whether a filling or shuttle thread breaks, or a warp breaks, the lever 115 will be actuated to raise the catch 117.

A hand lever 118 (Figs. 3 and 8), pivotally supported at 119, has a lug or shoulder 120 that is normally engaged by the catch 117, the lever 118 being held in the position

10 which it occupies when the loom is running, by said catch, a spring 121 shifting the lever when the catch releases it. The lower portion of lever 118 has a projection or stud 122, preferably ball-shaped at its end,

15 which engages an arc slot 123 formed in the upper arm of elbow lever 37. This arc slot is eccentric to the axis of pivot 119, the eccentricity being such that when the shoulder 120 is released by the catch 117, upon the 20 breakage of either warp or weft, the spring 121 throws the lever 118 so that the stud 122, traveling along the slot 123, oscillates the elbow lever 37 to effect the stoppage of the loom.

25 The operations of the several parts of the loom having been explained in connection with the description of the structure thereof, further explanation of the operation of the loom as a whole will not be necessary further than to state that, in general, it is the same as that of the loom described and claimed in my patent hereinbefore referred to.

It will be understood, of course, that when either the breakage of a filling thread or a 30 warp thread has caused the actuation of lever 115 of spring 121 the hand lever 118 causes the separation of the driving clutch members, and the machine stops. If the breakage was in a filling thread, the leading 35 of the thread back again through the eye of lever 64 (Fig. 2) will put the mechanism in condition to enable the machine to be started again by simply throwing the lever 118 (Fig. 8) over so that its shoulder 120 will 40 be reengaged by the catch 117. If the stoppage was due to the breakage of a warp, then the supply of a continuous warp thread again will elevate the hook pin 89 which it 45 dropped, and then the operator, by means of the handle 125 of pin 95 (Fig. 5) will 50 restore the ring members 91, 92, to their normal relative positions so that the pin 107 (Fig. 8) will return down the incline or 55 cam 111 and permit the spring 112 to raise the lever 110 and return the catch 117 to position to be reengaged by the shoulder 120 of the lever 118.

I do not limit myself to the specific details of constructions illustrated and described, 60 except as required by the scope of the following claims.

I claim:

1. In a circular loom, a cylinder having a series of separate vertical guides secured thereto, said guides having ways in their

opposing side faces, and warp-guiding slides mounted in the ways of said guides.

2. In a circular loom, a cylinder having a series of separate vertical guides secured thereto, said guides having ways in their 70 opposing side faces, warp-guiding slides mounted in the ways of said guides, and a ring connecting the lower ends of said guides.

3. In a circular loom, a cylinder having 75 a series of separate vertical guides secured thereto, said guides having ways in their opposing side faces, warp-guiding slides mounted in the ways of said guides, said guides having pairs of oppositely inclined wings, 80 and shuttles mounted to travel along the track provided by said wings.

4. A circular loom having a cylinder, a series of separate vertical guides secured to the inner wall of said cylinder and having ways in their opposing side faces, said guides having pairs of oppositely inclined wings to form a shuttle track, warp-guiding 85 slides mounted in the ways of said guides, and shuttles mounted on the track presented by said guides, each of the shuttles having 90 a base plate provided with gibs fitting said track.

5. In a circular loom, a shuttle comprising 95 a base-plate, a circular track therefor, a bobbin-supporting frame carried by said plate, a lever carried by said frame having an eye through which the thread passes from the bobbin to the weaving point, and movable members connected with and under the 100 control of said lever for stopping the machine upon the failure of the severed thread.

6. In a circular loom, a shuttle comprising 105 a base-plate, a circular track therefor, a bobbin-supporting frame carried by said plate, a lever carried by said frame having an eye through which the thread passes from the bobbin to the weaving point, a plunger connected with said lever and extending through the base-plate, said plunger being 110 connected to said lever and having means whereby it will be projected beyond the outer face of said base-plate upon failure of the shuttle thread, and means in the path of movement of said plunger to effect the 115 stopping of the loom.

7. In a circular loom, a shuttle comprising 120 a base-plate, a circular track therefor, a bobbin-supporting frame carried by said plate, a lever carried by said frame having an eye through which the thread passes from the bobbin to the weaving point, a plunger connected with said lever and extending through the base-plate, said plunger being 125 connected to said lever and having means whereby it will be projected beyond the outer face of said base-plate upon failure of the shuttle thread, and means in the path of movement of said plunger to effect the 130 stopping of the loom, said means including

a substantially radially mounted pin, a spring for projecting said pin, means for locking the pin in non-projected position until released by the action of said plunger, and a power-controlling catch adapted to be released by said pin when projected.

8. A circular loom having a series of vertically movable slides and means for actuating them, inwardly bowed guides, and warp-guides vertically movable with said slides and controlled laterally by said bowed guides.

9. A circular loom having a series of vertically movable slides and means for actuating them, inwardly bowed guides, warp-guides vertically movable with said slides and controlled laterally by said bowed guides, and a ring surrounding said bowed guides to support the warps on their way to the warp-guides.

10. A circular loom having a series of vertically movable slides and means for actuating them, wires pivotally connected to the upper ends of said slides, and inwardly bowed guides for swinging said wires, the upper portions of said wires having warp-eyes.

11. A circular loom having a series of vertically movable slides and means for actuating them, inwardly bowed guides, warp-eyes vertically movable with said slides and controlled laterally by said bowed guides, and a ring connecting the upper ends of said bowed guides.

12. A circular loom having a series of vertically movable slides and means for actuating them, wires pivotally connected to the upper ends of said slides, and inwardly bowed guides for swinging said wires, the upper portions of said wires having warp-eyes, warp-eyes being also provided adjacent the hinged points of said wires.

13. A circular loom having a stationary ring formed with a series of holes, a ring mounted to oscillate relatively thereto and having a series of holes, a series of pins having eyes for the warps and mounted in the holes of the stationary ring, and means controlled by the dropping of a pin into a hole of the oscillating ring to effect the stoppage of the loom.

14. A circular loom having a stationary

ring formed with a series of holes, a compound ring comprising two members yieldingly connected together and mounted to oscillate relatively to the stationary ring, one of the oscillating members having a series of holes, warp-thread pins mounted in the holes of the stationary ring and adapted to drop into one of the holes of the oscillating member upon failure of the warp, to lock the ring into which it drops, and means controlled by the other oscillating member to effect the stoppage of the loom.

15. A circular loom comprising in its construction a stationary ring, a series of warp eye pins mounted therein, two rings mounted below the stationary ring to oscillate relatively thereto, one of the last-mentioned rings having a series of holes equal to the said pins in number, said ring having also a pin, the other oscillating ring having a slot through which said pin projects and also having a pin, a spring connecting the pins of the oscillating rings, and means controlled by the lower oscillating ring to effect the stoppage of the loom.

16. In a circular loom a stationary ring having a series of vertically movable warp eye pins, upper and lower rings mounted to oscillate relatively to the stationary ring, means whereby the said two rings are yieldingly connected to oscillate together when permitted to do so, the lower ring having a lever connected to oscillate therewith, said lever having a cam, a pin projecting from the upper ring to engage said cam, and means connected with said cam-lever for effecting the stoppage of the loom.

17. A circular loom having a stationary ring provided with inner and outer ribs across which the warps are drawn, a series of vertically movable pins mounted in said ring and having eyes for the warps, and means to effect the stoppage of the loom upon the failure of a warp and the dropping of its eye pin.

In testimony whereof I have affixed my signature, in presence of two witnesses.

ABRAHAM E. CHERNACK.
